(57) **ABSTRACT**

A notification device includes a pressure sensor, a microcontroller and an output device. The pressure sensor is used to detect the environment to provide a plurality of sound signals in time domain. The microcontroller is used to calculate a dynamic threshold corresponding to a current time point based on the sound signals in time domain during a first time period prior the current time point. of the pressure signal in a period of time. When a magnitude of the sound signal in time domain at the current time point is greater than the dynamic threshold, the microcontroller sends a feedback signal to the output device. The output device is connected to the microcontroller. The output device is used to provide a feedback action according to the feedback signal.

CROSS-REFERENCE TO RELATED APPLICATIONS

This application is a continuation-in-part application of U.S. application Ser. No. 17/331,726, filed on May 27, 2021, which claims priority to Taiwan Application Serial Number 109117898, filed May 28, 2020 and Taiwan Application Serial Number 109206633, filed May 28, 2020, both of which are herein incorporated by reference in their entireties.

BACKGROUND

Field of Disclosure

The present disclosure relates to notification devices and wearable device with a notification device and notification methods.

Description of Related Art

In some workplaces, it is inconvenient to communicate directly through voice. For example, there are hearing impaired people in the workplace, or there is loud noise in the workplace. In these situations, workers remain isolated from the sound and it is not inconvenient to communicate. If you use other communication aids in the market, it may affect working. In such regard, how to provide a portable and instant notification device is one of the problems that people in the related fields want to solve.

SUMMARY

An aspect of the present disclosure is related to a notification device

According to one or more embodiments of the present disclosure, a notification device includes a sound sensor, a microcontroller and an output device. The sound sensor is configured to detect a plurality of sound signals in time domain from an environment. The microcontroller is connected to the sound sensor to receive the sound signals in time domain. The microcontroller is configured to generate a plurality of dynamic statistics of the sound signals in time domain during a first time period prior to a current time point. The microcontroller is configured to generate a dynamic threshold corresponding to the current time point by composing the dynamic statistics. The microcontroller is configured to provide the sound signals in time domain during a second time period following the current time point and convert the when a magnitude of the sound signal in time domain at the current time point is greater than the dynamic threshold. The microcontroller is configured to transmit a feedback signal corresponding to the sound signals in time domain during the second time period following the current time point. The output device is connected to the microcontroller. The output device is configured to provide a feedback action according to the feedback signal.

In one or more embodiments of the present disclosure, the notification device further includes a server. The server is connected to the microcontroller through a network. The server is configured to receive the sound signals in time domain during the second time period following the current time point. The server is configured to transmit the feedback

signal to the microcontroller according to a first sound type of the sound signals in time domain.

In some embodiments of the present disclosure, the server further includes a processor and a sound recognition module. The processor is configured to convert the sound signals in time domain during the second time period into a plurality of spectrograms. The sound recognition module is configured to recognize the spectrograms to obtain a plurality of probabilities of a plurality of sound types of the sound signals in time domain during the second time period, wherein the sound types include the first sound type.

In one or more embodiments of the present disclosure, the dynamic statistics includes an average value, a median value, a mode value, a maximum value, a minimum value, a standard deviation and a quartile deviation of the sound signals in time domain during the first time period.

In one or more embodiments of the present disclosure, the output device includes a light emitting device, a vibrator, a sound amplifier or a text icon display device.

An aspect of the present disclosure is related to a wearable device.

According to one embodiment of the present disclosure, a wearable device includes the mentioned notification device and a cloth. The pressure sensor, the microcontroller and the output device of the notification device are arranged on the cloth.

An aspect of the present disclosure is related to a notification method, which can be performed by the mentioned notification device.

According to one or more embodiments of the present disclosure, a notification method includes a number of operations. A plurality of sound signals in time domain is detected from environment. The sound signals in time domain during a first time period prior to a current time point are processed to obtain a plurality of dynamic statistics of the sound signals in time domain during the first time period. A dynamic threshold corresponding to the current time point is generated by the dynamic statistics. It is confirmed that whether a magnitude of the sound signals in time domain at the current time point is greater than the dynamic threshold. The sound signals in time domain during a second time period following the current time point are converted to a plurality of sound information in frequency domain when the magnitude of the sound signals in time domain at the current time point is greater than the dynamic threshold. The sound information in frequency domain are recognized to obtain a first sound type corresponding to the sound information. A feedback signal is transmitted to an output device based on the first sound type.

In one or more embodiments of the present disclosure, the dynamic statistics includes an average value, a median value, a mode value, a maximum value, a minimum value, a standard deviation and a quartile deviation of the sound signals in time domain during the first time period.

In one or more embodiments of the present disclosure, generating the dynamic threshold corresponding to the current time point by the dynamic statistics includes a number of operations. A plurality of candidate dynamic thresholds is generated, wherein each of the candidate dynamic thresholds is formed by the dynamic statistics and a plurality of weights corresponding to the dynamic statistics. The smallest one of the candidate dynamic thresholds is selected as the dynamic threshold.

In one or more embodiments of the present disclosure, the current time point changes over time, so that the first time period and the second time period change relative to the current time point.

In one or more embodiments of the present disclosure, the sound information in frequency domain are a plurality of spectrograms.

In one or more embodiments of the present disclosure, recognizing the sound information in frequency domain further includes a number of operations. A plurality of time intervals all within the second time period is generated. The sound signals in time domain during the time intervals are converted into the sound information

In some embodiments, one or more of the time intervals are overlapped from each other.

In some embodiments, the sound information in frequency domain are a plurality of spectrograms. Recognizing the sound information in frequency domain further includes a number of operations. The spectrograms are recognized to obtain a plurality of probabilities corresponding to a plurality of sound types for each of the spectrograms, wherein the sound types comprise the first sound type.

In some embodiments, recognizing the sound information in frequency domain further includes a number of operations. A notification threshold corresponding to the first sound type is set. The feedback signal corresponding to the first sound type is provided when an accumulation of the probabilities for the first sound type during that second time period is greater than that notification threshold.

An aspect of the present disclosure is related to a notification method, which can be performed by the mentioned notification device.

According to one or more embodiments of the present disclosure, a notification method includes a number of operations. Sounds are detected from environment and a plurality of conditions corresponding to the sounds from the environment is provided to establish a sound recognition module in a server. A plurality of sound signals in time domain is detected from environment. The sound signals in time domain during a first time period prior to a current time point are processed to obtain a plurality of dynamic statistics of the sound signals in time domain during the first time period. A dynamic threshold corresponding to the current time point is generated by the dynamic statistics. It is confirmed whether a magnitude of the sound signals in time domain at the current time point is greater than the dynamic threshold. The sound signals in time domain during a second time period following the current time point are transmitted to the server. The sound signals in time domain during the second time period is recognized to obtain a first sound type of the sound signals in time domain during the second time period, wherein the first sound type corresponds to one of the condition. A feedback signal corresponding to the first sound type is provided. A feedback action is provided by an output device according to the feedback signal to notify an user wearing the output device

In one or more embodiments of the present disclosure, the dynamic statistics includes an average value, a median value, a mode value, a maximum value, a minimum value, a standard deviation and a quartile deviation of the sound signals in time domain during the first time period.

In one or more embodiments of the present disclosure, generating the dynamic threshold corresponding to the current time point by the dynamic statistics further includes a number of operations. A plurality of candidate dynamic thresholds is generated, wherein each of the candidate dynamic thresholds is formed by the dynamic statistics and a plurality of weights corresponding to the dynamic statistics. The smallest one of the candidate dynamic thresholds is selected as the dynamic threshold.

In one or more embodiments of the present disclosure, the current time point changes over time, so that the first time period and the second time period change relative to the current time point.

In one or more embodiments of the present disclosure, recognizing the sound information in frequency domain by the sound recognition module further includes a number of operations. A plurality of time intervals all within the second time period is generated. The sound signals in time domain during the time intervals are converted into the sound information, wherein the sound information are a plurality of spectrograms. The spectrograms are recognized to obtain a plurality of probabilities corresponding to a plurality of sound types for each of the spectrograms, wherein the sound types comprise the first sound type. A notification threshold corresponding to the first sound type is set. The feedback signal corresponding to the first sound type is provided when an accumulation of the probabilities for the first sound type during that second time period is greater than that notification threshold.

In summary, the present disclosure provides a notification device, a wearable device using the notification device, and a corresponding notification method to notify the user in real time according to the environmental volume, so that the user can easily perceive changes in the environment.

It is to be understood that both the foregoing general description and the following detailed description are by examples, and are intended to provide further explanation of the invention as claimed.

BRIEF DESCRIPTION OF THE DRAWINGS

The advantages of the present disclosure are to be understood by the following exemplary embodiments and with reference to the attached drawings. The illustrations of the drawings are merely exemplary embodiments and are not to be considered as limiting the scope of the present disclosure.

FIG. 1 illustrates a block diagram of a notification device according to an embodiment of the present disclosure;

FIG. 2 illustrates a flowchart of a notification method according to an embodiment of the present disclosure;

FIG. 3 illustrates a block diagram of a notification device according to an embodiment of the present disclosure;

FIG. 4 illustrates a block diagram of a server according to an embodiment of the present disclosure;

FIG. 5 illustrates a flowchart of a notification method provided by a notification device according to an embodiment of the present disclosure;

FIG. 6 illustrates a flowchart of a training method of training a sound recognition module according to an embodiment of the present disclosure;

FIG. 7 illustrates a flowchart of a training method of training a classification module according to an embodiment of the present disclosure;

FIGS. 8-10 respectively illustrate a front view of a wearable device, a back view of the wearable device and a perspective view of the inside of the pocket of a wearable device according to an embodiment of the present disclosure;

FIG. 11 illustrates a method 700 for notifying according to one or more embodiments of the present disclosure; and

FIG. 12 illustrates a time line with one or more times in the method 700 for notifying according to one or more embodiments of the present disclosure.

DETAILED DESCRIPTION

The following embodiments are disclosed with accompanying diagrams for detailed description. For illustration

clarity, many details of practice are explained in the following descriptions. However, it should be understood that these details of practice do not intend to limit the present invention. That is, these details of practice are not necessary in parts of embodiments of the present invention. Furthermore, for simplifying the drawings, some of the conventional structures and elements are shown with schematic illustrations. Also, the same labels may be regarded as the corresponding components in the different drawings unless otherwise indicated. The drawings are drawn to clearly illustrate the connection between the various components in the embodiments, and are not intended to depict the actual sizes of the components.

In addition, terms used in the specification and the claims generally have the usual meaning as each terms are used in the field, in the context of the disclosure and in the context of the particular content unless particularly specified. Some terms used to describe the disclosure are to be discussed below or elsewhere in the specification to provide additional guidance related to the description of the disclosure to specialists in the art.

The phrases "first," "second," etc., are solely used to separate the descriptions of elements or operations with the same technical terms, and are not intended to convey a meaning of order or to limit the disclosure.

Additionally, the phrases "comprising," "includes," "provided," and the like, are all open-ended terms, i.e., meaning including but not limited to.

Further, as used herein, "a" and "the" can generally refer to one or more unless the context particularly specifies otherwise. It will be further understood that the phrases "comprising," "includes," "provided," and the like used herein indicate the stated characterization, region, integer, step, operation, element and/or component, and does not exclude additional one or more other characterizations, regions, integers, steps, operations, elements, components and/or groups thereof.

Reference is made by FIG. 1. FIG. 1 illustrates a block diagram of a notification device 1 according to an embodiment of the present disclosure. As shown in FIG. 1, the notification device 1 includes a sound sensor 10, a microcontroller 20 and an output device 30. Through the notification device 1, the user can be notified in real time according to changes in the environment.

The sound sensor 10 is used to detect environment to receive sound signals in the environment. When the notification device 1 is configured in an environment such as a warehouse or a factory, the received sound signal is, for example, the sound of engineering equipment or the human voice of other workers, and the received sound signal is an analog signal. In some embodiments, the sound sensor 10 is, for example, a microphone sensing module (for example, condenser microphone), or may be a condenser microphone sensing module simply arranged in an array.

A microcontroller (microcontroller, or named as microcontroller unit, MCU for short) 20 is connected to the sound sensor 10. The microcontroller 20 has the advantages of small size, easy portability, and can be configured to implement simple arithmetic functions. The sound sensor 10 can transmit the sound signal to the microcontroller 20, and the sound signal from the sound sensor 10 is simply processed by the microcontroller 20. The microcontroller 20 can also integrate a function for judging the volume of the sound signal. Therefore, the microcontroller 20 can record a sound signal over a period of time and provide a feedback signal according to the volume change of the sound signal.

The output device 30 is connected to the microcontroller 20 to provide a feedback action based on the feedback signal. The output device 30 can include a light emitting device, a vibrator, a sound amplifier, or a text icon display device. The text icon device directly reminds the user more intuitively by displaying text or other icons. The text icon display device includes a small portable display.

Therefore, the notification device 1 can detect the environment through the sound sensor 10 to provide sound signals. The microcontroller 20 connected to the sound sensor 10 processes the dynamic average value of the sound signals over a period of time. The dynamic average value refers to the average volume of the sound signals in the previous period of time. Based on the dynamic average value, a dynamic threshold can be predetermined. If a volume of the current sound signal is greater than the dynamic threshold calculated by the dynamic average value of the previous period, it means that the environment has changed, there may be danger or there is a need for communication around, and the microcontroller 20 provides a feedback signal to the output device 30, so that the output device 30 provides a feedback action to notify the user.

In some embodiments, instead of the sound sensor 10, other types of pressure sensors can also be used as the notification device 1. A kind of pressure sensor is the sound sensor 10, which is used to sense and convert the sound pressure change in the sound transmission in the environment into sound signals and then calculate a dynamic average value to obtain a dynamic threshold. In some embodiments, other types of pressure sensors such as air pressure sensors can be used as the notification device 1. For example, the air pressure sensor can sense the dynamic average value of the air pressure during a period of time. Once the current air pressure value is greater than the dynamic average value calculated in the previous period, the microcontroller 20 can send a feedback signal to enable the output device 30 to provide a feedback action to immediately notify the user who uses the notification device 1.

Reference is made by FIG. 2 to further describe how to notify the user by the notification device. FIG. 2 illustrates a flowchart of a notification method 600 according to an embodiment of the present disclosure. The notification method 600 includes operation 610-650.

In operation 610, the sound sensor 10 of the notification device 1 can be used to detect environment around the user to obtain sound signals during a period of time.

In operation 620, the sound signals can be processed by the microcontroller 20 connected to the sound sensor 10 to obtain the dynamic threshold during a period of time. The microcontroller 20 can first calculate the dynamic average value of the volumes of the sound signals during a period of time according to the sound signals. For example, the sound sensor 10 can obtain a dynamic average value of the volumes during the period from 3 seconds ago to 1 second ago. After the notification device 1 is activated, the dynamic average value may change in times continuously.

According to the dynamic average value, the microcontroller 20 can define the dynamic threshold of the volumes of the sound signals in different times, so as to determine whether the volumes of the sound signals have a large change in a short time. In some embodiments, the dynamic threshold can be set as the dynamic average value. In some embodiments, it can be set that the dynamic threshold is different from the dynamic average value according to the magnitude of the dynamic average value. For example, if the dynamic average value of the volumes of the sound signal is less than a specific decibel (dB), the dynamic threshold is set

to a value greater than the dynamic average value; and if the dynamic average value of the volumes of the sound signals is greater than the specific decibel, the set dynamic threshold is directly equal to the dynamic average value.

Through operation 620, the dynamic average value of the volumes of the received sound signal is set. In the process 630, it can be determined whether a volume of a current sound signal is greater than the dynamic threshold according to the current volume of the sound signal. If yes, the operation 640 is entered, and a feedback signal is sent to the output device 30. If not, return to operation 610 and continue to detect the environment to provide sound signals.

For example, in a specific embodiment, the dynamic average volume of the volumes of the sound signals from 3 seconds ago to 1 second ago is calculated by the microcontroller 20 calculates and is a specific decibel value (e.g., 60 dBs), and the dynamic average value of the volumes of the sound signals is set as the dynamic threshold by the microcontroller 20 (operation 620). Then, once the current volume of the sound signal is greater than the dynamic threshold (for example, greater than 60 dBs), the situation corresponds to the determination of operation 630 as yes, the operation 640 is entered and the microcontroller 20 can provide a feedback signal to the output device 30 in real time.

Therefore, in the operation 650, the output device 30 can provide an appropriate feedback action based on the feedback signal from the microcontroller 20 to notify the user who uses the notification device 1. The notification method 600 can be implemented by a mobile device. For example, mobile devices such as smart phones have a microphone, a processor, and a vibrator configured to vibrate the phone. The installation of an application (APP) is performed on the smart phone for the notification, and it enables the microphone to act as the sound sensor 10, the processor of the mobile phone functions as the microcontroller 20, and the vibrator of the mobile phone acts as the output device 30 to provide notification vibration feedback action.

Reference is made by FIG. 3. FIG. 3 illustrates a block diagram of a notification device 100 according to an embodiment of the present disclosure. The notification device 100 is built on the basis of the notification device 1 and can further provide intelligent notification and alert functions in addition to the function of the notification device 1. As shown in FIG. 3, the notification device 100 includes a sound sensor 110, a microcontroller 120, a server 130, an output device 150, and a distance sensor 160. In this embodiment, the sound sensor 110, the output device 150, and the distance sensor 160 are connected to the microcontroller 120, and the server 130 is located remotely, for example, connected to the microcontroller 120 by a network. The server 130 can be used for complex computation. Since the server 130 can be located remotely, when the notification device 100 is operated, only the sound sensor 110, the microcontroller 120, the output device 150, and the distance sensor 160 need to be carried. In some embodiments, the network is, for example, a wireless network shared by a mobile phone of the user. In some embodiments, the microcontroller 120 can be connected to the network through Bluetooth communication. In some embodiments, the network may be another type of wireless network (Wi-Fi), such as Zigbee. In some embodiments, the network may also be narrow band Internet of things (narrow band Internet of things, NB IoT) of a fourth-generation mobile communication technology (4G) or LTE-M technology. In some embodiments, the network may be provided by the fifth-generation mobile communication technology (5G) to achieve faster transmission rate and interaction.

The sound sensor 110 is similar to the sound sensor 10 in FIG. 1. The sound sensor 110 is used to detect the environment to receive sound signals in the environment. For example, when the notification device 100 is used in an environment such as a warehouse or a factory, the received sound signals are, for example, the sounds of engineering equipment or the human voice of other workers, which are analog signals. Specifically, in some embodiments, the sound sensor 110 is, for example, a microphone sensing module. The microphone sensing module is, for example, a condenser microphone. In some embodiments, the condenser microphone sensing modules can also be simply arranged in an array.

In order to facilitate analysis, the received analog sound signals can be processed to filter noises after the sound signals from the environment are received by the sound sensor 110. In some embodiments, other devices used for filtering noise can also be provided on the sound sensor 110.

The microcontroller 120 is similar to the microcontroller 20 in FIG. 1. The microcontroller 120 is connected to the sound sensor 110. The microcontroller 120 has the advantages of small size, easy portability, and can be used to implement simple arithmetic functions. Furthermore, the microcontroller 120 can be connected to a remote server 130 by a network. Through the connection with the microcontroller 120, the sound sensor 110 can transmit the sound signals to the microcontroller 120. In some embodiments, the network can be provided by, for example, a mobile phone.

The server 130 is located remotely and used to perform more complicated operations. Reference is made by FIGS. 3 and 4. FIG. 4 illustrates a block diagram of the server 130 according to an embodiment of the present disclosure. In this embodiment, the server 130 includes a sound recognition module 135, a classification module 140, and a processor 145. In some embodiments, the sound recognition module 135, the classification module 140, and the processor 145 are computer components in the server 130. In some embodiments, the sound recognition module 135, the classification module 140, and the processor 145 can be integrated into the same hardware.

The sound recognition module 135 is configured for recognizing sound signals. The classification module 140 is configured to classify types of the recognized sound signals. The processor 145 is configured to provide a feedback signal according to the types of the sound signals. For details, please refer to specific operation methods below. Through the remote transmission of the network, the microcontroller 120 can be used to receive the feedback signal from the server 130 remotely.

The output device 150 is connected to the microcontroller 120 to provide feedback actions according to the feedback signals. The output device 150 is similar to the output device 30 in FIG. 1 and includes a light emitting device, a vibrator, a sound amplifier, or a text icon display device. The text icon display device includes a small portable display. In order to cope with the inconvenient environment for communicating with voice, in some embodiments, the feedback action of the output device 150 does not include voice/sound feedback.

The distance sensor 160 is connected to the microcontroller 120 to detect the distance between the notification device 100 and an object. For example, the distance sensor 160 is, for example, an ultrasonic distance sensing device. In some embodiments, the distance sensor 160 uses infrared rays for distance sensing, or uses millimeter-wave radar or

sub-millimeter-wave radar. Due to the used short wavelength, it can have a wider sensing range to detect objects in a great angular range.

Reference is made by FIG. 5. FIG. 5 illustrates a flowchart of a notification method 200 provided by a notification device 100 according to an embodiment of the present disclosure.

In operation 210 of the notification method 200, the sound sensor 110 of the notification device 100 detects environment to obtain analog sound signals.

Following the operation 210, in the operation 220, the analog sound signals are transmitted by the microcontroller 120 to the server 130 through, for example, a network.

In operation 230, the analog sound signals are recognized by the sound recognition module 135 of the server 130. Through the recognition of the sound recognition module 135, the server 130 can obtain the sounds contained in the analog sound signal, such as the warning sound from a person, the specific content of the warning sound, and/or the sound of engineering equipment.

In operation 240, types of the analog sound signals can be classified through the classification module 140 of the server 130. In the operation 250, feedback signals are outputted by the server 130 according to the types of the sound signals. In other words, a type of the sound signal can correspond to a kind of feedback signal. A type of the sound signal is classified according to the response after the sound signal is received, and the type is used for warning of danger or call communication, for example.

In some embodiments, the sound signals in the working environment can be classified into plurality of types, and each of the types of the sound signals corresponds to a condition, and the condition corresponds to one of feedback actions. A number of the types of sound signals is finite and can be customized and introduced according to the conditions.

For example, in some implementations, there is only one type “dangerous” of the sound signals. The sound signal is received by the notification device 100 (operation 210) and uploaded to the server (operation 220), a recognition of the sound signal is completed (operation 230), and then it learns that the content of the sound signal is to inform the user that it is dangerous (e.g., the content of the sound signal can be a sound of working equipment or human voice), and the sound signal can be classified as “dangerous” by the notification device 100 at this time, so that a corresponding feedback signal is outputted by the server 130 to the output device 150 to notify the user of the notification device 100 that the user is at risk.

Specifically, in another practical example, there are six types of sound signals including dodging to the left if danger appears, dodging to the right if danger appears, vibrating, other types of danger, moving to the right, and reminding to be called by someone. For example, a sound signal is received by the notification device 100 (operation 210) and uploaded to the server (operation 220), the recognition of the sound signal is completed (operation 230), and then the content of the sound signal is to notify the user that the right side is dangerous and the user should dodge to the left. At this time, the sound signal is classified into the type “dodging to the left if danger appears” by the notification device 100 (operation 240). Subsequently, a feedback signal about dodging to the left is outputted by the server 130 (operation 250).

In some embodiments, the distance sensor 160 can also be used to provide information about the environment near around the user of the notification device 100, so that much

accurate judgments can be provided by the server 130. For example, in some embodiments, a large-size work equipment moves from the rear right to the user of the notification device 100. At the same time, the sound signals of the large-size equipment sound are detected by the sound sensor 110 and an approach of an object from the rear right is detected by the distance sensor 160, so that the server 130 can identify and classify that the type of the sound signal is about dodging to the left according to the above information, thereby providing a feedback signal about dodging to the left.

Continued with operation 250, in the operation 260, the feedback signal from the server 130 is received by the microcontroller 120 remotely via the network.

In the operation 270, a feedback action is performed by the output device 150 connected to the microcontroller 120 according to the received feedback signal. For example, the output device 150 can be a vibrator placed on the left and right shoulders of the user. When the feedback signal about dodging to the left is received by the microcontroller 120, the vibrator on the left shoulder of the user vibrates, so that the vibrator on the left shoulder of the user vibrates in real time through the sense of touch and a warning is issued to the user of the notification device 100.

In some embodiments, the notification device 100 can be further connected to a console. The console can be used to manage one or more notification devices 100 or wearable devices with the notification devices 100 at the same time. For example, the console can actively send a feedback signal to a specific one of the notification devices 100 to directly drive the output device to perform a warning. Accordingly, the proactive notification provided in the above manner can further strengthen the warning function of the notification device 100. In some embodiments, the console can further configure one or more notification devices 100 into different groups, so as to notify a specific group or all notification devices 100 in different conditions in environment with loud-noise.

In this embodiment, the sound recognition module 135 and the classification module 140 can be trained through machine learning to provide customized recognition and classification of sound signals in response to different types of working environments. In details, please refer to following discussion.

Reference is made by FIG. 6. FIG. 6 illustrates a flowchart of a training method 300 of training a sound recognition module 135 according to an embodiment of the present disclosure.

As illustrated in figures, in operation 310, the sound sensor 110 is used to detect the environment to obtain analog sound signals. The user of the notification device 100 can select different detection environments according to actual needs.

In some embodiments, the sound sensor 110 can detect the signal according to the signal detection theory (SDT) by dynamically detecting the sound.

In operation 320, after the sound sensor 110 detects the analog sound signals in the environment, the analog sound signals are converted into digital sound files in time domain through digital processing. In some embodiments, the digital processing can be performed by the microcontroller 120. In some embodiments, the digital processing can also be performed remotely by the server 130. In some embodiments, the digital sound files in time domain can be further divided into several specific sound blocks according to time through frame blocking processing and the signals in individual sound blocks are processed and analyzed.

11

Continued with operation 320, in operation 330, the digital sound files in time domain is transformed into digital sound files in frequency domain. Specifically, the digital sound files in time domain can be transformed into digital sound files in frequency domain through the server 130 or other computer devices connected to the server 130 in a manner of fast Fourier transform (FFT). In some embodiments, by creating digital sound files in frequency domain, a spectrogram, which corresponds to the amplitudes of the digital sound files in time domain at different frequencies at different times, can be further obtained.

Continued with operation 330, in operation 340, characteristic values of the digital sound files in frequency domain are extracted through a sound characteristic value extraction module. The sound characteristic value extraction module is configured in the server 131. The characteristic values of the digital sound files in frequency domain correspond to different kinds of sounds. For example, the sounds from engineering equipment and human voice have different characteristics, and these characteristics response in the spectrum or spectrogram of the sound, for example. By analyzing the spectrum or spectrogram of the digital sound files in frequency domain, the characteristic values of the digital sound files in frequency domain can be extracted from the spectrum or spectrogram, so as to distinguish the difference between the sound produced by the engineering equipment and the human voice.

For example, the sound characteristic value extraction module can be performed by the use of Mel-Frequency Cepstral Coefficients (MFCCs) method. Through the calculation module of sound characteristic value extraction module, the digital sound files in frequency domain can be converted into the corresponding Mel-Frequency Cepstrum (MFC) to obtain the corresponding Mel-Frequency Cepstrum Coefficients (MFCCs). The Mel-Frequency cepstrum coefficients can be used as the characteristic value of the digital sound files in frequency domain, so that what kinds of the digital sound files in frequency domain can be obtained, the kinds of the digital sound files in frequency domain are, for example, the sound of engineering equipment or human voice. In some embodiments, Deep Neural Networks (DNN) technology in the field of artificial intelligence can be used in the sound characteristic value extraction module to extract the characteristic values of the digital sound files in frequency domain. Deep neural network technology has a good performance in image recognition. Therefore, conceptually, the digital sound files in frequency domain can be converted into an image, and the sound corresponding to the image of the digital sound files in frequency domain can be identified by image recognition to obtain the corresponding characteristic value.

Specifically, in one embodiment, the server 130 includes a convolutional neural network (CNN) model. In the deep neural network technology, the convolutional neural network module can effectively realize the function of image recognition. A sequence of spectrograms provided by other sounds can be pre-input to the convolutional neural network model, so that the training of image recognition of the convolutional neural network model can be performed and completed. One sequence of spectrograms may refer to the frequency amplitude distribution diagrams at different times arranged in a time sequence. For example, a plurality of sets of corresponding sequence of spectrograms can be provided as the basis for image recognition for the sound of working equipment or human voice. In some embodiments, the sound used to train the convolutional neural network model is sampled in the actual working environment, so as to create

12

a customized recognition scheme according to the actual environment. Therefore, after the learning of image recognition for the convolutional neural network model is completed, the convolutional neural network model can receive 5 input of another sequence of spectrograms. The convolutional neural network model obtains the similar sound of another sequence of spectrograms through image recognition and then outputs a corresponding characteristic value. According to requirements of the user of the notification 10 device 100, analog sound signals in the environment can be detected, the analog sound signals can be converted into digital sound files in frequency domain, and then a training 15 is performed based on the files of existing human voices or sound of tools and instruments by inputting the digital sound files in frequency domain.

Therefore, another implementation manner of operation 340 can be implemented as follows. First, convert the digital sound file in frequency domain into a sequence of spectrograms. The spectrogram shows changes in the amplitudes of 20 different frequencies over time. Here, a sequence of frequency amplitude distribution diagrams of digital sound files in frequency domain at different times can be output. Then, a sequence of spectrograms of the digital sound file in frequency domain is input into the convolutional neural 25 network model in the sound characteristic value extraction module, and the characteristic value of the digital sound file in frequency domain can be output by the convolutional neural network model.

In operation 350, the sound recognition module 135 can 30 be trained according to the digital sound files in frequency domain and their characteristic value. The training of the sound recognition module 135 can be applied by deep neural networks in the field of artificial intelligence. Each of the characteristic value of the digital sound file in frequency 35 domain corresponds to a kind of the human voice or sounds tools and instruments. When a characteristic value of a digital sound file in frequency domain indicates that it is a human voice, the message content corresponding to the digital sound file in frequency domain is further input to the 40 sound recognition module 135 to train the sound recognition module 135. When the characteristic value of the digital sound file in frequency domain indicates that it is the sound of a tools and instruments, corresponding condition information can be provided. Therefore, when the trained sound 45 recognition module 135 receives the sound signal, it can identify whether the sound signal is a human voice or the sound of a tool or an instrument. If the sound signal is a human voice, the content of the message to be conveyed can be determined. If the sound signal is sound of a tool or an instrument, a corresponding situational information can be provided. In some embodiments, the microcontroller 120 50 can be directly connected to a single-chip computer, and the edge calculation of sound recognition can be realized on the premise of being easy to carry. For example, the single-chip 55 computer includes raspberry pi.

FIG. 7 illustrates a flowchart of a training method 1400 of training a classification module 140 according to an embodiment of the present disclosure. Similar to the voice recognition module 135, the classification module 140 can also 60 achieve customized training through a deep neural network. The classification module 140 is used to distinguish the types of different analog sound signals to provide appropriate feedback signals.

In operation 410, analog sound signals are input. In 65 operation 420, the input of the analog sound signals is recognized by, for example, the sound recognition module 135.

13

Then, in operation 430, the condition information corresponding to the analog sound signals are input. For example, when an analog sound signal is input, the analog sound signal can be recognized that is about message of dodging to the left from someone, and the corresponding condition is to dodge to the left at this time.

In operation 440, the classification module 140 can be trained according to the analog sound signals and their corresponding conditions. Specifically, the recognized analog sound signals are used as input, the corresponding specific conditions are used as the training target, and the classification module 140 can be trained to classify the recognized analog sound signal into different conditions. The different conditions are, for example, the condition of dodging to the left as mentioned above. Different conditions correspond to different types of the sound signals. Therefore, the notification device 100 is substantially integrated with a wireless network and can also personalize the setting of artificial intelligence identification parameters, so that the server 130 can receive different condition information for retraining. This is an implementation of the Internet of Thing (IoT) architecture of the overall service of the notification device 100 of the present disclosure. In addition, the microcontroller 120 can also implement a warning function beyond the Internet of Things architecture. For example, the microcontroller 120 integrated with the function of judging the volume of the sound signal can be used to detect abnormal changes in the environmental volume, so as to send another feedback signal for warning notification. The specific flow is similar to flowchart in FIG. 2, and the notification device 100 can perform the same function as the notification device 1. Therefore, in an environment where there is no network, the notification device 100 can also implement a warning notification function.

Reference is made by FIGS. 8, 9 and 10. FIGS. 8-10 respectively illustrate a front view of a smart vest 500, which is a wearable device, a back view of the wearable device and a perspective view of the inside of the pocket of the wearable device according to an embodiment of the present disclosure. In this embodiment, the notification device 100 is installed on a vest 505 to serve as a smart vest 500. In some embodiments, other cloth beyond the vest 505 can also be used.

Please refer to FIGS. 8 and 9. As shown in figures, the smart vest 500 includes a front 510, a back 530, and a shoulder 520 connecting the front 510 and the back 530. The front 510 is provided with a pocket 513 to accommodate the mobile phone and provide internet access. The back 530 of the smart vest 500 is also provided with a pocket 533. The pocket 533 is used to house and fix the components of the notification device 100, which includes the sound sensor 110, the distance sensor 160 and the circuit board 170.

As shown in FIG. 10, the sound sensor 110 of the notification device 100, the microcontroller 120, the power supply module 180 for supplying power, and the distance sensor 160 are integrated on the support plate 170. The power supply module 180 includes a battery and a switch. The wires can be integrated on the top, inside the interlayer, or on the opposite side of the circuit board 170.

In this embodiment, the sound sensor 110, the distance sensor 160 and the circuit board 170 are arranged in the pocket 533 on the back 530 of the smart vest 500. Since the eyes of the user are not easy to look at the back, the sound sensor 110 and the distance sensor 160 used for detecting environment are arranged on the back 530 of the smart vest 500, which can better play the role of the notification device 100 to detect danger and issue a warning. In some embodi-

14

ments, the exposed parts of the sound sensor 110 and the distance sensor 160 are provided with a waterproof structure to adapt to different environmental changes. In this embodiment, the output device 150 provided on the smart vest 500 includes a light bar 153 and a vibrator 156. The vibrator 156 is connected to the circuit board 170 through a wire 185.

In summary, the present disclosure provides a notification device and a wearable device using the notification device. The notification device can detect the volume of the environment in a period of time, so as to notify the user in real time when the volume of the environment changes. The notification device can also connect to the server remotely by the microcontroller using the network. It is easy to carry and the server can recognize and classify the received sound signals to provide feedback based on the type of the sound signals. The type of the sound signal is, for example, human voice or sound of engineering equipment. The wearable device is, for example, a smart vest combined with a notification device, which is convenient to wear. By installing output devices such as a vibrator and a light bar on it, the user can easily perceive changes in the environment by means other than sound, which is conducive to real-time communication and warning. The notification device is also set to facilitate customized training to provide more accurate recognition and warning effects in different working environments.

Reference is made in FIGS. 11 and 12 to further illustrate one or more embodiments for notifications responding to different sound types of sound signals. FIG. 11 illustrates a notification method 700 according to one or more embodiments of the present disclosure. FIG. 12 illustrates a time line with one or more times in the method 700 for notifying according to one or more embodiments of the present disclosure.

In one or more embodiments, once a particular type of sound is present in the environment, it will be possible to perform a notification method 700 to efficiently detect and notify the user of the particular type of sound. In one or more embodiments of the present disclosure, the notification method 700 can be implemented by the notification device 1 or the notification device 100. For example, in one or more embodiments of the present disclosure, the notification device 100 may be an integrated mobile device, including, for example, a cellular phone. In one or more embodiments of the present disclosure, the notification device 100 may be carried by a user as part of a wearable device.

In operation 701, a plurality of sounds from environment is detected from environment, and the sounds are classified so as to obtain a plurality of sound types.

In one or more embodiments of the present disclosure, operation 701 can be performed by the notification device 1 or the notification device 100. For example, a plurality of analog sound signals from the environment can be detected by the sound sensor 10 of the notification device 1 or the sound sensor 110 of the notification device 100. The sounds contained in the analog sound signals from the environment can be obtained. For example, the sounds contained in the analog sound signals can be human voices from different humans or equipment sounds from different tools and instruments.

In some embodiments, the analog sound signals are then soundly recognized by the sound recognition module 135 of the notification device 100. The sound recognition module 135 can be provided by a method similar to the method 300.

In some embodiments, the sounds contained in the analog sound signals can be further classified by the classification module 140 of the notification device 100, and a plurality of

sounds types of the sounds from the environments can be obtained. The sound types provided by the classification module **140** correspond to different conditions appearing in the environment. In some embodiment, the classification module **140** can be trained in the operation **701** through a method similar to the method **400**.

It should be noted that a number of the sounds types of the sounds from the environment can be customized through the operation **701**. That is, different numbers of the sound types can be selected for the different environment. For example, the environment in which the sounds are obtained from can be a closed factory environment or an open environment since the tools and instruments are different in the closed factory environment or the open environment, and a number of the sounds from the closed factory environment can be different from a number of the sounds from the open environment. Accordingly, in one or more embodiments of the present disclosure, the numbers of the sound types can be customized for different environment, and it would be helpful to the further recognition operations of method **700**.

In operation **702**, a plurality of sound signals in time domain is detected from the environment.

In one or more embodiments of the present disclosure, the sound signal from the environment can be continuously detected by the sound sensor **10** of the notification device **1** or the sound sensor **110** of the notification device **100** to obtain changes in the pressure variation of the sound signal at different times in the environment. It should be noted that the time-domain sound signals detected by the sound sensor **110** is the variation of the sound signal over the time domain, and the time-domain sound signals include volumes in decibels of the sound signals at different times.

In this embodiment, a current time is time point P_i , where the index i corresponds to a different time. As shown in FIG. 12, the time point P_1 is the current time point. The sound sensor **110** can continuously detect the sound signals in time domain from another time point P_{11} prior to the current time point P_1 . The time point P_{12} follows the time point P_1 . The sound sensor **110** can continuously detect the sound signals in time domain between the current time point P_1 and the time point P_{12} . In FIG. 12, the current time point P_1 is at time t_1 second. The time point P_{11} is at time t_1-T_1 second and the time point P_{11} is earlier than current time point P_1 by a time period T_1 . Time point P_{12} is at time t_1+T_2 second, and the time point P_{12} is later than the current time point P_1 by a time interval T_2 . Time point P_{13} is at time t_1+T_3 second and the time point P_{13} is later than the current time point P_1 by a time period T_3 .

In one or more embodiments of the present disclosure, when the sound signals in time domain are detected by the sound sensor **110**, time period T_1 , time interval T_2 or time period T_3 can be further cut into a plurality of time intervals to detect the sound signals in time domain in the different time intervals. For example, as shown in FIG. 12, in this embodiment, a time of a frame can be defined as a time period Δt . Within the time period T_1 , the volume of the sound signal is detected from the environment for each frame as one of the detected sound signals in time domain. In some embodiments, for example but not limited to, the time period T_1 can be set to 2 seconds and the time period Δt can be set to 0.0001 seconds (corresponding to 10,000 Hz), so as to slice the time period T_1 into 10,000 frames, and then detect the different volume at these 10,000 frames as the sound signals in time domain.

For example, in some embodiments, after the sound sensor **110** detects the analog sound signals in time domain from the environment, the analog sound signals in time

domain are converted into digital sound files in time domain by a digital processing. In some embodiments the digital processing can be performed by the microcontroller **120**. In some implementations, the digital processing can also be performed remotely via the server **130**. In some embodiments, the digital sound files in time domain can be further segmented into several specific sound blocks through an audio frame blocking processing, and the digital sound signals in time domain in each of the sound blocks can be processed and analyzed.

In one or more embodiments of the present disclosure, the time period T_1 between the current time point P_1 and the time point P_{11} can be considered as a detection period to confirm whether to perform sound recognition for the time period T_3 following the current time point P_1 . For details, please refer to the subsequent description.

In operation **703**, a plurality of statistics S_{iy} of the sound signals in time domain during the detection period T_1 prior to the current time point P_i are generated.

In this embodiment, the index i corresponds to different times (e.g., time point P_1), and the index y corresponds to different types of statistics. For the current time point P_1 ($i=1$), a plurality of statistics generated by the sound signals in time domain during the detection period T_1 prior to the current time point P_1 are presented as dynamic statistics S_{1y} .

In one or more embodiments of the present disclosure, operation **703** may be executed through the microcontroller **120** programmed in notification device **100**. In one or more embodiments of the present disclosure, by contacting server **130** via microcontroller **120**, operation **703** may be executed by one or more processors and memories in the server **130**.

For example, in one or more embodiments of the present disclosure, the time period T_1 can be divided into a plurality of sound blocks by the time period Δt , so that a plurality of sound signals in time domain are detected at different sound blocks in the time period T_1 between the current time point P_1 and time point P_{11} . The sound signals in time domain are, for example, volumes. Therefore, the sound signals in time domain are statistically processed to obtain an average value S_{11} , a median value S_{12} , a mode value S_{13} , a maximum value S_{14} , a minimum value S_{15} , a standard deviation S_{16} and an quartile deviation S_{17} of the sound signals in time domain during the time period T_1 between the current time point P_1 and the time point P_{11} .

In operation **704**, a plurality of candidate dynamic thresholds CDT_{ix} is induced according to the statistics (e.g., the average value S_{11} , the median value S_{12} , the mode value S_{13} , the maximum value S_{14} , the minimum value S_{15} , the standard deviation S_{16} and the quartile deviation S_{17}) of the sound signals in time domain during the detecting time period T_1 , and the smallest one of the candidate dynamic thresholds CDT_{ix} as a dynamic threshold DT_i for the current time point P_i .

In this embodiment, the index i of the candidate dynamic thresholds CDT_{ix} corresponds to different time point P_i , and the index x corresponds to the different kinds of the candidate dynamic thresholds CDT_{ix} .

Specifically, in one or more embodiments of the present disclosure, after, the statistics S_{iy} (e.g., the average value S_{11} , the median value S_{12} , the mode value S_{13} , the maximum value S_{14} , the minimum value S_{15} , the standard deviation S_{16} and the quartile deviation S_{17}) for the sound signals in time domain during the time period T_1 prior to the current time point P_1 (corresponding to $i=1$) are provided, and a candidate dynamic threshold can be formed by the statistics S_{1y} and expressed by the following relation (1):

$$CDT_{1x} = \sum_{y=1}^7 W_{xy} S_{1y}$$

The statistics S_{1y} are the average value S_{11} , the median value S_{12} , the mode value S_{13} , the maximum value S_{14} , the minimum value S_{15} , the standard deviation S_{16} and the quartile deviation S_{17} . Coefficients W_{xy} are weights, which have different values corresponding to different statistics S_{1y} . In some embodiment, $-\alpha < W_{xy} < \beta$, wherein α, β are positive integers. In one or more embodiments of the present disclosure, one or more statistics can be further considered.

According to the above relation (1), in one or more embodiments of the present disclosure, one or more candidate dynamic thresholds CDT_{ix} can be provided for the time period $T1$ prior to the current time point $P1$. In one or more embodiments of the present disclosure, one or more sets of weights W_{xy} are designed to induce one or more candidate dynamic thresholds CDT_{ix} for different types of environments. For example, a factory and a road are two different environments. Different sets of the weights W_{xy} can be used for different environments. Alternatively, unexpected deviations of the statistics S_{1y} are caused by a plurality of conditions/situations in the same environment appears or intrinsic differences between the sound sensors **10**/sound sensors **110** to be used, and the unexpected deviations of the statistics S_{1y} can be reduced by the designed candidate dynamic thresholds CDT_{ix} .

In order to clearly illustrate how to create candidate dynamic thresholds CDT_{ix} for the current time point $P1$ in operation **704**, several examples of candidate dynamic thresholds are provided below.

In one or more embodiments of the present disclosure, the candidate dynamic threshold CDT_{ix} may include the candidate dynamic threshold CDT_{11} , where in the relation (1) for calculating the candidate dynamic threshold CDT_{11} , the weight $W_{11}=1$ and the weights $W_{12}, W_{13}, W_{14}, W_{15}, W_{16}$ and W_{17} are zero. In this case, the relation (1) for the calculation of the dynamic threshold CDT_{11} can be expressed as

$$CDT_{11} = \sum_{j=1}^7 W_{1y} S_{1y} = W_{11} S_{11} = S_{11}$$

In other words, the candidate dynamic threshold CDT_{11} is equal to the average value S_{11} of the sound signals in time domain during the period $T1$ prior to time point $P1$. In this case, the candidate dynamic threshold CDT_{11} is similar to the dynamic threshold of notification method **600**, wherein dynamic threshold of notification method **600** is determined by a dynamic average value.

In one or more embodiments of the present disclosure, the candidate dynamic threshold CDT_{ix} may include the candidate dynamic threshold CDT_{12} , wherein in the relational equation for calculating the candidate dynamic threshold CDT_{12} , the weight $W_{21}=1$, $W_{26}=-1$, and the weights $W_{22}, W_{23}, W_{24}, W_{25}$, and W_{27} are all zero. In this case, the relation (1) for the calculation of the dynamic threshold CDT_{12} can be expressed as

$$CDT_{12} = \sum_{j=1}^7 W_{2y} S_{1y} = W_{21} S_{11} + W_{26} S_{16} = S_{11} - S_{16}$$

In other words, the candidate dynamic threshold CDT_{12} is equal to the average value S_{11} minus the standard deviation S_{16} of the sound signal in time domain during the period $T1$ prior time point $P1$.

Therefore, the candidate dynamic thresholds CDT_{11} and CDT_{12} are calculated. In the set of candidate dynamic thresholds CDT_{11} and CDT_{12} , since the candidate dynamic threshold CDT_{12} is less than the candidate dynamic threshold CDT_{11} , the candidate dynamic threshold CDT_{12} is selected as the dynamic threshold DT_1 for the current time point $P1$.

Accordingly, the dynamic threshold DT_i of the detected sound signals in time domain can be used to determine whether a user needs to be notified. In one or more embodiments of the present disclosure, operation **704** may also be performed by the microcontroller **120** programmed in the notification device **100**. In one or more embodiments of the present disclosure, operation **704** may be communicated with the server **130** via microcontroller **120** to be executed via one or more processors and memory in server **130**.

In operation **705**, determine whether a magnitude of the sound signal in time domain at the current time point Pi is greater than the dynamic threshold DT_i of the current time point Pi .

In this embodiment, it is verified whether the volume received at the current time point $P1$ is greater than the dynamic threshold DT_1 obtained from the time period $T1$ prior to the current time point $P1$. If no, it returns to operation **702** and continues to detect the sound signals in time domain from the environment. If yes, proceed to operation **706**, further sound recognition and notification operations are performed.

In one or more embodiments of the present disclosure, the dynamic threshold DT_1 reflects the volume prior to the current time point $P1$. In operation **705**, if the magnitude of the sound signal in time domain at the current time point $P1$ is greater than the dynamic threshold, it means that a significant change in the sound signal in time domain at the current time point $P1$ relative to the sound signal in time domain during the period $T1$ prior the current time point $P1$ appears, so as to proceed to operation **706** to perform further identification operations.

It should be noted that the dynamic threshold DT_1 of the current time point $P1$ is determined by the statistics S_{1y} of the sound signals in the time period $T1$ prior to the current time point $P1$. To obtain the dynamic threshold DT_2 for another time point $P2$, it must be determined by the statistics S_{2y} of the sound signals in time domain during other time period $T1$ prior to time point $P2$. The statistics S_{2y} include an average value S_{21} , a median value S_{22} , a plural value S_{23} , a maximum value S_{24} , a minimum value S_{25} , a standard deviation S_{26} , and an quartile deviation S_{27} of the sound signals in time domain during the period $T1$ prior to the time point $P2$.

In other words, as the current time point Pi changes continuously over time, the time period $T1$ changes correspondingly and the statistics S_{iy} of the sound signals during the time period $T1$ prior the current time point Pi also change dynamically. For example, the dynamical statistics S_{iy} may include a dynamic mean value S_{i1} , a dynamic median value S_{i2} , a dynamic mode value S_{i3} , a dynamic maximum value S_{i4} , a dynamic minimum value S_{i5} , a dynamic standard deviation S_{i6} , and a dynamic quartile deviation S_{i7} of the sound signals in time domain during the period $T1$ prior to the time point Pi . The dynamic threshold DT_i , which is formed by the dynamic statistics S_{iy} , will also change over time.

In one or more embodiments of the present disclosure, operations **705** may also be executed through the microcontroller **120** programmed in notification device **100**. In one or more embodiments of the present disclosure, operations **705** may be communicated with the server **130** via the microcontroller **120** to be executed via one or more processors and memory in server **130**.

In some embodiments, the total duration of operation of the notification device **1** or the notification device **100** after activation is less than duration of the time period **T1**. If the notification device **1** or notification device **100** performs the calculation of operation **705**, it may cause the statistical data to be calculated out of order. In this case, a pre-designed value can be used to replace the dynamic threshold of failure, so that the notification device **1** or notification device **100** can still determine whether the identification operation needs to be performed later in the short operation time.

In operation **706**, the sound signals in time domain during a recognition time period **T3** following the current time point **Pi** (e.g., current time point **P1**) are provided. In some embodiments, as the current time point **Pi** changes over time, the time period **T3** would also change relative to the current time point **Pi**.

On the time line as illustrated in FIG. 12, the time period **T3** is between the time point **P1** and the time point **P13**. The time point **P13** is later than the time point **P1** by the time period **T3**.

In one or more embodiments of the present disclosure, once the operation **706** is entered, the sound signals in time domain may be continuously provided to the server **130** via the microcontroller **120**. For example, the sound signals in time domain during the time period **T3** following the current time point **P1** are transmitted to the server **130** by the microcontroller **120**. The time period **T3** can be considered as a recognition time period. Upon confirmation of a significant change in the sound signals in time domain at the current time point **P1**, the user is further notified via the server **130** of what type of sound the sound signals in time domain is in the time period **T3** following the current time point **P1**.

In the view from operation **703** to operation **706**, dynamic thresholds can be set to determine whether the sound signals in time domain during the time period **T3** following the current time point **P1** should be sent to the server **130**.

For example, if the magnitude of the sound signals in time domain at the current time point **P1** is less than the dynamic threshold, it reflects that no significantly change between the sound signals in time domain at the current time point **P1** and the sound signals in time domain during the time period **T1** prior to the current time point **P1** is provided, and no alert is issued to notify the user.

In another example, if the magnitude of the sound signal in time domain at the current time point **P1** is greater than the dynamic threshold, it reflects that a significantly change between the sound signals in time domain at the current time point **P1** and the sound signals in time domain during the time period **T1** prior to the current time point **P1** appears, and a further recognition operation must be performed to notify the user.

Therefore, it will be able to efficiently save numbers of the sound signals that need to be transmitted and processed. If there is a change in the environment, the dynamic threshold is used to confirm whether the sound signals in time domain have changed enough to determine whether further recognition of the sound signals in time domain are required.

In operation **707**, after the sound signals in time domain during the time period **T3** following the current time point

P1 are received by the server **130** the sound signals in a plurality of time intervals **T2** in the recognition time period are converted into a plurality of spectrograms corresponding to the time intervals **T2** in frequency domain. In this embodiment, each of the time intervals **T2** has the same duration. As shown in FIG. 12, one or more time points (e.g., time point **P1**, time point **P2**, and time point **P3**) are provided in the time period **T3** between time point **P1** and time point **P13**. One of the time intervals **T2** is extended from the time point **P1** to the time point **P13**.

In this embodiment, each of the time intervals **T2** has the same time duration. As shown in FIG. 12, the time period **T3** between time point **P1** and time point **P13** includes a plurality of time points including the time point **P1** at the boundary of time period **T3**, the time point **P2**, and time point **P3**. One of the time intervals **T2** extends from time point **P1** to time point **P12**.

According to FIG. 12, a time difference between time point **P2** and time point **P1** is less than one of the time interval **T2**. Therefore, another time interval **T2** extending from time point **P2** to time point **P22** overlaps with time interval **T2** extending from time point **P1** to time point **P12**. In other words, in one or more embodiments of the present disclosure, the selected time intervals **T2** in time period **T3** are overlapping with each other.

In addition, as shown in FIG. 12, another time interval **T2** extends from time point **P3** to time point **P13**, which makes the time interval **T2** extending from time point **P3** extend just beyond the boundary of time period **T3**. Since other time periods **T2** starting later than time point **P3** will be beyond the boundary of time period **T3**, time interval **T2** extending from time point **P3** is the last time interval processed by operation **707**.

It should be noted the time line shown in FIG. 12 is for illustrative purposes only and should not be used to unduly limit this disclosure.

For the purpose of simple description, in one or more embodiments of the present disclosure, it is possible to set the time interval **T2** to be 2 seconds, the time period **T3** to 40 be 4 seconds, and a plurality of time points starting at each time period **T2** to be spaced 0.1 seconds apart. In this case, based on time point **P1** at time **t1** second, the operation **707** will be able to convert multiple sound signals in time domain into spectrums or spectrograms for the following time intervals: time interval from time **t1** second to time **t1+2** second, time interval from time **t1+0.1** second to time **t1+2.1** second, time interval from time **t1+0.2** second to time **t1+2.2** second, . . . , and time interval from time **t1+2** second to time **t1+4** second for a total of 20 time intervals. In operation **707**, the sound signals in time domain during the 20 time intervals are converted into spectrums or spectrograms. The spectrums or spectrograms are the sound information corresponding to time interval **T2** in frequency domain, and the spectrums or spectrograms reflect the intensity of sound signals at different frequencies during time interval **T2**. The used of the plurality of the time intervals **T2** during the time period **T3** is able to response a continuous appearance of a sound of one of the sound types.

In one or more embodiments of the present disclosure, the microcontroller **120** can provide time-domain digital sound files of the sound signals in time domain during the time periods **T2** following the current time point **P1** to the server **130** or other computer devices connected to the server **130**, so that a fast Fourier transform (FFT) operation is performed 60 to convert the time-domain digital sound files to digital sound files in frequency domain. The FFT is used to convert the time-domain digital sound files to the digital sound files

21

in frequency domain. Therefore, a plurality of spectrums or spectrograms corresponding to multiple time intervals **T2** in the time period **T3** following the current time point **P1** can be obtained. The spectrums or spectrograms are the sound information corresponding to time intervals **T2** in frequency domain. In some embodiments, the FFT for the sound signals in time domain can be performed by the processor **145** of the server **130**.

In operation **708**, recognize the spectrums or spectrograms corresponding to the time intervals **T2** in the recognition time period **T3** to obtain a plurality of probabilities corresponding to different sound types.

In some embodiments, the operation **708** may be performed by the sound recognition module **135** trained in the server **130**. In some embodiments, the sound recognition module **135** can be trained by the method **300**. The trained sound recognition module **135** in the server **130** performs image recognition of the sound spectrum map (i.e., sound information in frequency domain) generated by the operation **707** and outputs the probabilities correspond to the sound spectrums or spectrograms map.

In details, a plurality of sound types includes engineering instrument sounds, human voices or other sound types. For a specific current time point P_i , the probabilities of N of sound types in the time interval **T2** following the time point P_i respective have the probabilities $Prob_{i1}$, $Prob_{i2}$, $\dots$, $Prob_{iN}$, and the sum of these probabilities can be expressed by the following relation (2)

$$\sum_{j=1}^N Prob_{ij} = 1$$

The indexes i in the above relation (2) corresponds to different time points P_i . The indexes j in the above relation (2) corresponds to different sound types (e.g. human voice or engineering equipment sound). N is the number of the sound types for the environment. In this embodiment, the number N is determined by the operation **701**, and probabilities of sound not appearing in the environment would be reduced to zero. The relation (2) can be regarded as a normalization relation to inhibit that the sound would not appear in the environment.

In other words, each of the probabilities $Prob_{i1}$, $Prob_{i2}$, $\dots$, $Prob_{iN}$ is in a range between zero and one, and the sum of the probability assignment values $Prob_{i1}$, $Prob_{i2}$, $\dots$, $Prob_{iN}$ sum to one.

For example, the sound recognition module **135** recognizes the sound spectrum of the time interval **T2** following the time point **P1** ($i=1$) in the time period **T3**, and the first sound type (e.g., human voice) has the probability $Prob_{11}$, the second sound type (e.g., engineering equipment sound) has the probability $Prob_{12}$, and so on. The sound recognition module **135** can recognize N types of sound types. In this way, the probabilities output by the sound recognition module **135** include probabilities $Prob_{11}$, $Prob_{12}$, $\dots$, $Prob_{iN}$, and the probabilities $Prob_{11}$, $Prob_{12}$, $\dots$, $Prob_{iN}$ are designed to satisfy the following relation (2)

$$\sum_{j=1}^N Prob_{1j} = 1$$

In another embodiment, the sound recognition module **135** recognizes the sound spectrogram of the time interval

22

T2 following another time point **P2** ($i=2$) in the time period **T3**, and the first sound type (e.g., human voice) has the probability $Prob_{21}$, the second sound type (e.g., engineering equipment sound) has the probability $Prob_{22}$, and so on. The sound recognition module **135** can recognize N types of sound types. In this way, the probabilities outputted by the sound recognition module **135** include probabilities $Prob_{21}$, $Prob_{22}$, $\dots$, $Prob_{2N}$, and the probabilities $Prob_{21}$, $Prob_{22}$, $\dots$, $Prob_{2N}$ are designed to satisfy the following relation (2)

$$\sum_{j=1}^N Prob_{2j} = 1$$

Therefore, in operation **708**, sound recognition is performed for different time intervals starting from different time points **P1**, **P2**, and **P3** in time period **T3**, and multiple probabilities corresponding to multiple different sound types in different time intervals are obtained.

In operation **709**, determine whether an accumulation of the probabilities of a first sound type is greater than a notification threshold of the first sound type in the recognition time period **T3**. If no, there is no need to notify for the first sound type and go back to operation **702**. If yes, go to the subsequent operations **710** and **711**.

Specifically, in order to avoid misclassification, the consistency of the sound recognition results in the time intervals starting from multiple different time points can be considered in operation **709**. For example, for a first sound type of the sound types determined by operation **701**, the notification threshold NT_1 for the first sound type can be designed, and it is verified that the probabilities $Prob_{11}$, $Prob_{21}$, $\dots$ for multiple first sound types derived in time period **T3** are higher than the designed notification threshold for the first sound type. The accumulation of the probabilities of multiple first sound types can be expressed by the following relation (3)

$$\sum_{i=1}^Q Prob_{i1} \geq NT_1$$

The index I corresponds to different time points in time period **T3**, and a number of the different time points in time period **T3** is Q .

Similarly, for a second sound type ($j=2$) of the sounds types, it can be confirmed whether an accumulation of probabilities of the second types is greater than a designed notification threshold for the second sound type. That is, the accumulation of the probabilities of multiple first sound types can be expressed by the following relation (3)

$$\sum_{i=1}^Q Prob_{i2} \geq NT_2$$

In some embodiment, for example but not limited to, the notification threshold NT_1 for the first sound type is, for example, 1. In this way, once the probability of the first sound type in one of the time interval **T2** in the time period **T3** is 100%, i.e., one of the probabilities $Prob_{11}$, $Prob_{21}$, $\dots$, $Prob_{Q1}$ is equal to 1, operation **709** determines that the cumulative probability of the first sound type during

the recognition time period T_3 is greater than the notification threshold NT_1 of the first sound type, so that following operation **710** is proceeded.

In some embodiments, for example but not limited to, the notification threshold NT_1 for the first sound type can be a number greater than 1. In some embodiment, the notification threshold NT_1 for the first sound type can be 6. Since each of the probabilities $Prob_{11}, Prob_{21}, \dots, Prob_{Q1}$ is a number in a range between zero and one, the accumulation of the probabilities $Prob_{11}, Prob_{21}, \dots, Prob_{Q1}$ is greater than 6 if multiple ones of the probabilities $Prob_{11}, Prob_{21}, \dots, Prob_{Q1}$ is non-zero. That is, the sound of the first sound type appears continuously in the recognition time period T_3 , a further notification operation must be performed, and following operation **710** is proceeded.

In one or more embodiments of the present disclosure, different notification thresholds NT_j can be set for different sound types. For example, in some embodiments, if the first sound type of the different sound types is human voice and the second sound type of the different sound types is engineering instrument sound, the notification threshold NT_1 of the first sound type of human voice can be set to be less than the notification threshold NT_2 of the second sound type of engineering instrument sound such that it is more sensitive to a recognition of human voice.

In one or more embodiments, since a sum of the probabilities of different sound types in one of the time intervals during the recognition time period T_3 is normalized, the notification thresholds NT_j (e.g. the notification threshold NT_1 for the first sound type and the notification threshold NT_2 for the second sound type) can be designed so that only one of the accumulations of the probabilities for the different sound type during the recognition time period T_3 has a value greater than the corresponding notification thresholds NT_j .

In one or more embodiments of the present disclosure, for the same sound type in different environments, different notification thresholds can be designed. For example, in a closed factory environment, the human voice can be easily ignored. In some embodiments, the notification threshold of the first sound type in the closed factory environment is less than the notification threshold of the first sound type in an open environment, so that it is more sensitive to identify the human voice in the closed factory environment.

In some embodiments, the operation **709** can be performed by an integration of the sound recognition module **135** and the classification module **140** of the notification device **100**. The classification module **140** is configured to limit the number N of sound types in which the sound recognition module **135** recognizes. Therefore, the computing cost for the sound recognition module **135** can be reduced.

Following operation **709**, in operation **710**, a feedback signal corresponding to the first sound type is outputted. In some embodiments, the microcontroller **120** receives feedback signals from the server **130** remotely over a network. For example, in some embodiments, the feedback signal corresponding to the first sound type can be provided by the classification module **140** of the server **130**, and the feedback signal corresponds to one of the condition in the environment. In some embodiments, the classification module **140** can be trained by the method **400**.

In operation **711**, a feedback action is provided based on received feedback signals to inform a presence of a sound with the first sound type in the environment for the user. In some embodiments, the output device **150** connected to the microcontroller **120** makes a feedback action based on the received feedback signal. For example, the output device

150 can be a vibrator set on the user to alert the user of the notification device **100** in real time by tactile.

In summary, the notification method **700** enables the recognition and notification of the sound signals in different environments in an adaptive manner. Number of sound types can be limited and customized for different environments. Dynamic threshold used to perform a recognition operation at a current time point can be determined based on the dynamic statistics during a time period prior to the current time point. An efficient recognition operation can be performed according to the sound signals filtered by the dynamic threshold and the limited sound types of the environment.

Although the present invention has been described in considerable detail with reference to certain embodiments thereof, other embodiments are possible. Therefore, the spirit and scope of the appended claims should not be limited to the description of the embodiments contained herein. In view of the foregoing, it is intended that the present invention cover modifications and variations of this invention provided they fall within the scope of the following claims.

What is claimed is:

1. A notification device, comprising:
a sound sensor configured to detect a plurality of sound signals in time domain from an environment;
a microcontroller connected to the sound sensor to receive the sound signals in time domain, wherein the microcontroller is configured to:

generate a plurality of dynamic statistics of the sound signals in time domain during a first time period prior to a current time point;
generate a dynamic threshold corresponding the current time point by composing the dynamic statistics, comprising:

generating a plurality of candidate dynamic thresholds, wherein each of the candidate dynamic thresholds is formed by the dynamic statistics and a plurality of weights corresponding to the dynamic statistics; and selecting the smallest one of the candidate dynamic thresholds as the dynamic threshold;

provide the sound signals in time domain during a second time period following the current time point when a magnitude of the sound signal in time domain at the current time point is greater than the dynamic threshold, and

transmit a feedback signal corresponding to the sound signals in time domain during the second time period following the current time point; and
an output device connected to the microcontroller, wherein the output device is configured to provide a feedback action according to the feedback signal.

2. The notification device of claim 1, further comprising:
a server connected to the microcontroller through a network, wherein the server is configured to receive the sound signals in time domain during the second time period following the current time point, and the server is configured to transmit the feedback signal to the microcontroller according to a first sound type of the sound signals in time domain during the second time period.

3. The notification device of claim 2, wherein the server further comprises:
a processor configured to convert the sound signals in time domain during the second time period into a plurality of spectrograms; and
a sound recognition module configured to recognize the spectrograms to obtain a plurality of probabilities of a

25

plurality of sound types of the sound signals in time domain during the second time period, wherein the sound types comprises the first sound type.

4. The notification device of claim 1, wherein the dynamic statistics comprises an average value, a median value, a mode value, a maximum value, a minimum value, a standard deviation and a quartile deviation of the sound signals in time domain during the first time period.

5. The notification device of claim 1, wherein the output device comprises a light emitting device, a vibrator, a sound amplifier or a text icon display device.

6. A wearable device, comprising:

the notification device of claim 1; and
a cloth, wherein the sound sensor, the microcontroller and the output device of the notification device are arranged on the cloth.

7. A notification method, comprising:

detecting a plurality of sound signals in time domain from environment;

processing the sound signals in time domain during a first time period prior to a current time point to obtain a plurality of dynamic statistics of the sound signals in time domain during the first time period;

generating a dynamic threshold corresponding to the 25 current time point by the dynamic statistics, comprising:

generating a plurality of candidate dynamic thresholds, wherein each of the candidate dynamic thresholds is formed by the dynamic statistics and a plurality of weights corresponding to the dynamic statistics; and selecting the smallest one of the candidate dynamic thresholds as the dynamic threshold;

confirming whether a magnitude of the sound signals in time domain at the current time point is greater than the dynamic threshold;

converting the sound signals in time domain during a second time period following the current time point to a plurality of sound information in frequency domain when the magnitude of the sound signals in time domain at the current time point is greater than the dynamic threshold;

recognizing the sound information in frequency domain to obtain a first sound type corresponding to the sound information; and

transmitting a feedback signal to an output device based on the first sound type.

8. The notification method of claim 7, wherein the dynamic statistics comprises an average value, a median value, a mode value, a maximum value, a minimum value, a standard deviation and a quartile deviation of the sound signals in time domain during the first time period.

9. The notification method of claim 7, wherein the current time point changes over time, so that the first time period and the second time period change relative to the current time point.

10. The notification method of claim 7, wherein the sound information in frequency domain are a plurality of spectrograms.

11. The notification method of claim 7, wherein recognizing the sound information in frequency domain further comprises:

generating a plurality of time intervals all within the second time period; and

converting the sound signals in time domain during the time intervals into the sound information in frequency domain.

26

12. The notification method of claim 11, wherein one or more of the time intervals are overlapped from each other.

13. The notification method of claim 11, wherein the sound information in frequency domain are a plurality of spectrograms, recognizing the sound information in frequency domain further comprises:

recognizing the spectrograms to obtain a plurality of probabilities corresponding to a plurality of sound types for each of the spectrograms, wherein the sound types comprise the first sound type.

14. The notification method of claim 13, wherein recognizing the sound information in frequency domain further comprises:

setting a notification threshold corresponding to the first sound type; and

providing the feedback signal corresponding to the first sound type when an accumulation of the probabilities for the first sound type during that second time period is greater than that notification threshold.

15. A notification method, comprising:

detecting sounds from environment and providing a plurality of conditions corresponding to the sounds from the environment to establish a sound recognition module in a server;

detecting a plurality of sound signals in time domain from environment;

processing the sound signals in time domain during a first time period prior to a current time point to obtain a plurality of dynamic statistics of the sound signals in time domain during the first time period;

generating a dynamic threshold corresponding to the current time point by the dynamic statistics, comprising:

generating a plurality of candidate dynamic thresholds, wherein each of the candidate dynamic thresholds is formed by the dynamic statistics and a plurality of weights corresponding to the dynamic statistics; and selecting the smallest one of the candidate dynamic thresholds as the dynamic threshold;

confirming whether a magnitude of the sound signals in time domain at the current time point is greater than the dynamic threshold;

transmitting the sound signals in time domain during a second time period following the current time point to the server;

recognizing the sound signals in time domain during the second time period to obtain a first sound type of the sound signals in time domain during the second time period, wherein the first sound type corresponds to one of the condition;

providing a feedback signal corresponding to the first sound type; and

providing a feedback action by an output device according to the feedback signal to notify an user wearing the output device.

16. The notification method of claim 15, wherein the dynamic statistics comprises an average value, a median value, a mode value, a maximum value, a minimum value, a standard deviation and a quartile deviation of the sound signals in time domain during the first time period.

17. The notification method of claim 15, wherein the current time point changes over time, so that the first time period and the second time period change relative to the current time point.

18. The notification method of claim 15, wherein recognizing the sound signals in time domain further comprises:

generating a plurality of time intervals all within the second time period;
converting the sound signals in time domain during the time intervals into a plurality of sound information in frequency domain, wherein the sound information are 5 a plurality of spectrograms;
recognizing the spectrograms to obtain a plurality of probabilities corresponding to a plurality of sound types for each of the spectrograms, wherein the sound types comprise the first sound type; 10
setting a notification threshold corresponding to the first sound type; and
providing the feedback signal corresponding to the first sound type when an accumulation of the probabilities for the first sound type during that second time period 15 is greater than that notification threshold.
